[57] CLAIM

The ornamental design for a mammography imaging
machine, as shown and described.

DESCRIPTION

FIG. 1 is a perspective view of a mammography imaging
machine, showing my new design;

FIG. 2 is a top plan view thereof;

FIG. 3 is a front elevational view thereof;

FIG. 4 is a left side elevational view thereof;

FIG. 5 is a right side elevational view thereof;

FIG. 6 is a rear elevational view thereof;

FIG. 7 is a bottom plan view thereof; and,

FIG. 8 is a view similar to FIG. 5 shown in an alternate
position.
The broken line showing in FIG. 1 is for illustrative
purposes and forms no part of the claimed design.

FIG. 1

FIG. 2

FIG. 3

FIG. 4

FIG. 5

FIG. 6

FIG. 7

FIG. 8
